UNITED STATES PATENT OFFICE

164,930

TOY ELEPHANT

Norman Hollis, London, England, assignor to
Rosedale Associated Manufacturers Limited,
London, England, a British company

Application February 14, 1951, Serial No. 14,210
In Great Britain January 1, 1951

Term of patent 14 years

(Cl. D34—2)

To all whom it may concern:

Be it known that I, Norman Hollis, a subject of the King of Great Britain, Northern Ireland and the Isle of Man, resident of London W. 1, England, have invented a new, original, and ornamental Design for a Toy Elephant of which the following is a specification, reference being had to the accompanying drawing, forming part thereof.

Fig. 1 is a front perspective view of a toy elephant, showing my new design, and

Fig. 2 is a rear perspective view thereof.

I claim:

The ornamental design for a toy elephant, as shown.

NORMAN HOLLIS.
